ATTORNEY

UNITED STATES PATENT OFFICE.

EDWARD EMMERS, OF ROYERSFORD, PENNSYLVANIA.

LADY'S UNDERVEST.

1,152,405.

Specification of Letters Patent. Patented Sept. 7, 1915.

Application filed May 22, 1914. Serial No. 840,153.

To all whom it may concern:

Be it known that I, EDWARD EMMERS, a citizen of the United States, and resident of Royersford, county of Montgomery, and 5 State of Pennsylvania, have invented an Improvement in Ladies' Undervests, of which the following is a specification.

The object of my invention is to provide a lady's undervest which shall have capacity 10 for adaption in use to suit high or low necked garments or changes in climatic conditions; and has for a further object the capacity for adjustment to suit persons of different bust measure and thereby reduce 15 the number of "sizes" necessary to meet the commercial demand.

My invention is more particularly directed to the class of undervest set out in Letters Patent No. 1,058,954, granted to me under 20 date of April 15, 1913, wherein the shoulder straps are composed of four free ends with capacity for being coupled together in pairs in two ways, namely to make the garment have a relatively high or low cut bust, said 25 result being secured by transforming the V-cuts of the armholes into the bust and back portions for a low cut or V bust. In my present improvement I secure the same general advantages, but in addition thereto, I 30 provide a body portion of knitted fabric in which there are a plurality (preferably four) vertical portions adjacent to the neck or upper part, two of which may be of a relatively compact ribbed fabric, while the 35 remaining two portions may be of a different appearance and desirably of a relatively open work fabric; and the latter may be in alinement with the V cuts of the arm holes, so that in warm weather the garment will 40 be cool under the arms, and when re-adjusted to bring the arm holes around to the chest and back to provide low V cuts at the chest and back, the open work or different structure of knitted fabric will give a dif- 45 ferent and more artistic appearance at the bust than that given with the other or normal adjustment of the garment suitable for high bust use.

My invention further comprehends the 50 use of eight separate drawing tapes or ribbons, secured in pairs at the free ends of the shoulder strap tabs and extending through open lace edging at the upper chest and back portions and arm holes of the garment, the free ends of said tapes being tied in pairs, one under each arm and one at the 55 middle of the front and back of the garment. By the adjustment of these tapes, the bust, back and arm holes may be varied as to size to suit different persons and enable the garment to snugly fit the wearer. 60

My invention will be better understood by reference to the drawings, in which:—

Figures 1 and 2 are perspective views illustrating the use of my improved garment on 65 the wearer; Fig. 3 is a perspective view of the improved garment with the shoulder tabs disconnected; Fig. 4 is a perspective view illustrating the two forms of the fabric employed in the body of the garment; and Fig. 70 5 is an elevation showing a modification of the body fabric.

2 is the body portion of the garment and is preferably made of ribbed knitted fabric in tubular construction and having the two 75 forms of knitted structure 3 and 4 alternating around the body, the portions 3 being preferably of close knitted ribbed fabric and the portions 4 being preferably of a different character, desirably of more or less open 80 work. In practice these portions 3, 3, 4, 4, each occupy approximately one quarter of the full circumference of the body, but I do not restrict myself to these proportions, and neither do I confine myself to any particular type of knitted fabric making up the 85 two forms 3 and 4, as these may be widely varied to secure various artistic effects aside from their utility in my invention.

The upper edges of the parts 3 of the body 90 are shaped to form the high bust and back 5, which may, for appearance, be very slightly V shaped, and said edges are bound with open work lace 7. The upper edges of the parts 4 of the body are formed with 95 deep cuts 6 to form the arm holes and are bound with open work lace edging 8. The open work lace 7 and 8 is united to form four shoulder tabs 9, the free ends of which are adapted for connection in pairs for providing shoulder straps. As shown, these tabs are united at 15 by buttons and button holes and it will be seen that of the tabs on each side of the portions 3 of the body one will have a button and the other a button 105 hole, so that the tabs may be united in pairs to make the portions 6 into arm holes as in Fig. 1, or to make the portions 5 form the arm holes, and portions 6 low cut V bust and back portions, as shown in Fig. 2. This feature, broadly considered, corresponds to my former patent hereinbefore referred to; 110

however, in my present invention, not only is the garment capable of being transformed from a high bust to a low bust garment and vice versa, but I am also enabled to bring 5 into the bust portion a different character of fabric. Thus, the high bust is formed of the fabric portions 3 of relatively close looped fabric and hence reasonably warm, whereas when adjusted for a low V cut bust 10 the fabric portions 4 come to the front and back and may give a more delicate and artistic effect by the use of open work looped structure, which would be in better keeping with a low necked dress and give more comfort to the wearer. Furthermore, the more 15 open fabric portions 4 of the body fabric may reduce the warmth of the garment under the arms and this is desirable to most persons, especially when engaged in arduous 20 house or business work, in dancing, or exercise such as tennis or other games.

In place of continuing the character of fabric 4 throughout the whole length of the garment, it may be provided for by knitting, weaving or inserting, as indicated in 25 Fig. 5, at 4^a, in which it is continued for only a few inches below the tab and arm hole portions.

10 are tapes or ribbons extending through the open work lace edging 7 of the front and back and similarly, 12 are tapes or ribbons extending through the open work lace edging 8 of the arm holes. These tapes 10 and 15 12 are secured together in pairs at the free ends 14 of the shoulder tabs 9. By drawing on the two tapes 10 at the bust the width of the bust portion may be varied and held to the adjusted size by tying said tapes together as at 11. The same is true of the 20 back portion of the garment. Similarly, the size of the arm holes may be adjusted by drawing on the tapes 8 and tying them together at the bottom of the arm holes as at 13. In this way the bust, back and each 25 arm hole may be conveniently adjusted to suit different persons. If, now, the garment be readjusted for a low cut bust as aforesaid, the tapes 12 will enable the width of the bust to be adjusted to suit the person and insure 30 a close fitting upper edge to the garment, and especially is this advisable if the portions 4 are made of delicate open knitted fabric or inserting.

For economy the body 2 would usually be 35 of knitted tubular ribbed fabric in which the portions 3 may be of fine ribbed struc-

ture and portions 4 of wider ribbed structure, but I do not restrict myself to any special construction of the body to provide the distinctions in the structure and appearance of the portions 3 and 4. It will also 60 be apparent that only one portion 4 might be used if it was only desired to provide the bust with a different fabric in the low cut adjustment of the garment, but for symmetry and more effective results I prefer to 65 duplicate the portions 3 and 4 as illustrated and described.

While I have shown my improved garment in the form I have found well suited to its use, I do not restrict myself to the exact details, as these may be modified without departing from the spirit of the invention.

Having now described my invention, what I claim and desire to secure by Letters Patent is:—

75 1. A low necked undergarment having the borders of the chest and back portions provided with lace edging, combined with separately operative adjustable drawing tapes through each of said lace edgings of the 80 back and chest, one end of each of such tapes secured to the garment, and said tapes providing two co-operating free ends at the chest portion and two co-operating free ends at the back portion whereby the said chest 85 and back portions may be separately and independently adjusted as to size.

2. An undergarment having low cut chest and back portions and arm-holes in which the junctures of the chest and back portions 90 with the arm holes are each provided with shoulder straps having free ends arranged to be coupled in pairs so as to be capable of changing the chest and back portions into arm-holes and the arm-holes into chest and 95 back portions, combined with separate sets of drawing tapes threaded into the upper edges of the low cut chest and back portions and each set having one end of each tape secured in the respective shoulder straps and 100 the remaining ends free and adapted to be adjustably tied, whereby the chest and back portions may be independently adjusted as to size.

In testimony of which invention, I here- 105 unto set my hand.

EDWARD EMMERS.
